POWERED AMUSEMENT VEHICLE

Almer M. Davey, Calgary, Alberta, Canada, assignor to
Wichman Industries, Inc., Minneapolis, Minn., a cor-
poration of Minnesota

Filed June 25, 1962, Ser. No. 70,681

Term of patent 14 years

(Cl. D34—15)

FIG. 1

FIG. 2

FIG. 3

FIG. 1 is a perspective view of a powered amusement vehicle embodying my design;

FIG. 2 is a side elevational view of the same taken from the left of FIG. 1; and

FIG. 3 is a bottom plan view of the same.

The characteristic feature of my design resides in the particular recessed stepped seat portion within the housing, all as shown.

I claim:

The ornamental design for a powered amusement vehicle, as shown and described.
